[57] CLAIM

The ornamental design for an exterior surface configuration of a motor vehicle lever, as shown and described.

DESCRIPTION

FIG. 1 is a front view of an exterior surface configuration of a motor vehicle lever according to my novel design;

FIG. 2 is a perspective view from above an exterior surface configuration of a motor vehicle lever according to my novel design;

FIG. 3 is a left side view of an exterior surface configuration of a motor vehicle lever according to my novel design; and, FIG. 4 is a rear view of an exterior surface configuration of a motor vehicle lever according to my novel design.

The left and right side views of the motor vehicle lever are mirror images of one another. The broken lines showing depict environment and are not part of the claimed design.
